CLIP-LOADING CAP GUN

Walter Moe, Plainview, and Edwin A. Nielsen, Oceanside, N.Y., assignors to Ideal Toy Corporation, Hollis, N.Y., a corporation of New York

Filed Aug. 19, 1965, Ser. No. 480,954

10 Claims. (Cl. 42—57)

The present invention relates generally to cap guns and specifically to an improved toy gun wherein the cap storage and firing mechanisms are contained within a clip which may be inserted into and removed from the gun.

The traditional cap gun construction uses a hollow body in which is contained storage space for a roll of caps and a cap-firing mechanism composed of a number of levers which actuate a hammer and anvil apparatus. Access to this storage area is achieved through a removable wall or a hinged or pivoted door.

Actual automatic pistols, on the other hand, are provided with bullet-containing clips which are inserted upwardly through the handle of the gun. As each bullet is fired, the next bullet in the clip moves upwardly into a firing chamber to be fired by the actuating mechanism. Accordingly, it is desirable to provide in a cap gun a simulation of the clip arrangement which is found in real automatic pistols.

It is an object of the present invention to provide an improved cap gun. Specifically, it is an object of the present invention to provide a cap gun which incorporates a clip-loading arrangement.

One of the advantages of a clip-loading cap gun, in addition to the increased fidelity to the prototype, is the ease with which a child playing with the gun can reload the gun. The expended clip may be quickly removed and replaced by a new clip.

Therefore, it is a further object of the present invention to provide a clip mechanism for a cap gun which incorporates both the cap storage means and the cap-firing means in a single clip which may be quickly extracted from and inserted into a cap gun.

A still further advantage of a clip-loading cap gun is the absence of the normal requirement of an access panel to the cap storage and firing mechanism areas. This enables the designer to exercise a wide degree of design freedom because of the increased strength of the gun body resulting from the absence of large access ports.

In accordance with one illustrative embodiment of the present invention, there is provided a cap gun which comprises a body having a hollow handle which is so shaped to form a clip-receiving cavity. A clip of complementary shape to the cavity is provided with cap storage and cap advancement and firing means. A trigger is mounted on the body for movement between an inactive position and a firing position in operative relationship with the cap advancement and firing means when the clip is contained within the cavity. The toy gun further includes releasable latch means for releasably securing the clip within the clip-receiving cavity.

The above brief description, as well as further objects, features and advantages of the present invention, will be best understood by reference to the following detailed description of one presently preferred embodiment of the invention, when taken in conjunction with the accompanying drawings, wherein:

FIGURE 1 is a side elevational view of the gun in accordance with the present invention, with a portion broken away and showing the clip being inserted into the gun;

FIGURE 2 is an elevational view of the clip of the gun of FIGURE 1 with the cover of the clip removed;

2

FIGURE 3 is a perspective view of the cap advancement and firing means incorporated within the clip;

FIGURE 4 is a central sectional view of the gun of FIGURE 1 showing the clip in position within the gun;

5 FIGURE 5 is a sectional view taken along line 5—5 of FIGURE 4 looking in the direction of the arrows and showing the operation of the releasable catch means;

10 FIGURE 6 is a sectional view along the line 6—6 of FIGURE 4 illustrating the engagement of the clip within the gun;

FIGURE 7 is a sectional view along the line 7—7 of FIGURE 4 looking in the direction of the arrows;

15 FIGURE 8 is a sectional view along the line 8—8 of FIGURE 6 looking in the direction of the arrows. FIGURE 8 illustrates the beginning of the cap-firing sequence in the gun;

FIGURE 9 is an enlarged sectional view of a portion of FIGURE 8; and

20 FIGURE 10 is a view similar to that of FIGURE 9, but showing the mechanism immediately after the cap gun has been fired.

In the drawings there is illustrated a gun, generally designated by the numeral 10, which includes a gun body 12 and a removable clip 14. The gun body 12 is formed with a handle portion 16 and a barrel portion 18 and is generally illustrative in external configuration of actual automatic pistols. A trigger housing or guard 20 is formed in the normal location immediately forward of the handle portion 16 and, as may be best seen in FIGURE 4, 25 a trigger 22 is mounted on the body 12 at a trigger pivot 24. The trigger 22 is spring biased toward the front of the gun 10 by means of a coil spring 26 secured to the trigger at 28 and secured to the barrel portion 18 of the body 10 at lug 30. At its lower and rearward end, the 30 trigger 22 is formed with a firing extension 32. The trigger 22 is movable from an inactive position as shown in FIGURE 4 to an active position as shown in FIGURE 8 wherein the firing extension 32 protrudes into a clip-receiving cavity 34 formed in the hollow handle portion 16 of the gun 10. The cavity 34 is partially shown in FIGURE 1 and is that portion of the body 12 which is occupied by the clip 14 in FIGURES 4 and 8. When the trigger is moved into its firing position, the 35 firing extension 32 engages appropriate mechanisms in the clip 14 to fire caps in a manner which will be more fully described below.

Clip 14, in the present illustrative embodiment, is formed of a cast body 36 which has a side wall 38, a front wall 40, a rear wall 42 and a base wall 44. A sheet metal cover 46 is pivoted to the clip body 36 at pivot 48 and is movable between a closed position (solid lines in FIGURE 1) and an open position (dotted lines in FIGURE 1). The upper end of the clip is permanently open. Housed within the clip 14 is a cap storage chamber 50 at the lower end of the clip defined by the dividing wall 51 and cap firing and advancement mechanisms 52 on the upper end of the clip. A simple cylindrical post 54 is provided at the center of the cap storage area 50 about which a conventional roll of caps R may be mounted. A strip S of caps from the roll R is normally threaded upwardly between the dividing wall 51 and the rear wall 42 of the cap body 36. The rear wall is formed at its upper end with an anvil 56 against which the caps are exploded by an appropriate hammer.

60 65 The cap firing and advancement mechanism 52 comprises an actuating lever 58 which is pivotally mounted on post 60 extending upwardly from the side wall 38 of the clip body 36. At its forward end, the actuating lever 58 has a contact face 62 which is engaged by the firing extension 32 of the trigger 22 when the trigger is moved into its firing position. Also pivotally mounted on the post 60 is a hammer 64 which is formed with a hammer

face 66 at its upper end. As may be seen in, for example, FIGURE 10, the hammer face 66 hits flat against the anvil 56 to fire a cap. The hammer lever 64 is biased toward its rearward position against the anvil 56 by a stiff firing spring 68 which is engaged at one end against the front wall 40 of the clip body 36 and at its other end against a point along the length of the hammer lever 64. The hammer 64 is cocked by the actuating lever 58 through the engagement of a cocking tooth 70, at the upper end of the actuating lever 58, with the complementary hammer tooth 72 integrally formed on the hammer lever 64. When the trigger 22 is moved from its inactive position toward its firing position, the firing extension 32 pushes against the contact face 62 of the actuating lever 58 and the interengagement of the teeth 70, 72 moves the hammer lever 64 forwardly against the bias force of the firing spring 68. This may be best seen by inspecting the perspective view of FIGURE 3 or by comparing FIGURE 4 and FIGURE 8. The hammer 64 is released to explode a cap against anvil 56 when the cocking tooth 70 slips off hammer tooth 72. This action occurs as follows: The actuating lever 58 is mounted not only for pivotal movement about post 60 but also for translatory movement with respect thereto by means of the elongated opening 74 formed in the lever 58 (see FIGURES 9 and 10). A camming wall 76 on the lower and rearward end of the actuating lever 58 engages a camming post 78 formed on the clip body 36 part of the way through the cocking and firing movement of the actuating lever 58 causing the actuating lever to move upwardly (elongated slot 74 moving upwardly along the post 60). As may be seen in FIGURE 10 by comparing the dotted line position of the elements with the solid line position, the cocking and hammer teeth 70, 72 are moved out of engagement by the upward movement of the actuating lever 58 at the end of the movement of the trigger 22 into the firing position thereby releasing the hammer lever 64 and allowing it to move quickly forwardly under the bias force of the firing spring 68. The force of the spring 68 is sufficient to drive the hammer 64 and hammer face 66 against the anvil 56 at a rate fast enough and with a force great enough to explode a cap. When the trigger 22 is released, the actuating lever 58 returns to the position shown in FIGURE 4.

The strip S of caps is advanced with each firing by means of the advancement link 80 which is pivoted to the actuating link 58 at pivot 82. A coil spring 84 is secured between the advancement link 80 at 86 and a spring lug 88 and biases the link 80 and the actuating link 58 in a downwardly direction (see FIGURE 3). At its upward and rearward end, the advancement link 80 has an advancement nose 90 which engages against the strip S of caps to push same upwardly along the rear wall 42 as the actuating lever 58 is moved through its cocking motion. As may be seen by progressively inspecting FIGURES 4, 9 and 10, the advancement link 80 is effective to move the strip S of caps a unit distance for each cocking and firing motion. This unit distance is equal to the spacing between caps along the strip S. As may be seen in FIGURE 4, a locating lug 92 is provided on the side wall 38 of the clip body 36 to fix the starting point for the advancement mechanism and to prevent the advancement link 80 from pivoting too far downwardly. It should be appreciated that the advancement spring 84 serves not only to bias the advancement link 80 into engagement with the cap strip S, but also serves as the biasing force to return the actuating link 58 to its inactive position as shown in FIGURE 4.

The clip 14 is guided within the cavity 34 by the locating lugs 34a (see FIGURE 6) and is secured in the cavity 34 by means of a latching lug 94 formed on the rear wall 42 which engages a camming latch 96 mounted within the gun body 12. As may be seen best in FIGURES 5 and 6, the latching lug 94 is an elongated member. The latch 96 is formed with a camming wall 98

which, when the clip 14 is shoved upwardly into the clip-receiving cavity 34, is engaged by the upper end of the lug 94. The latch 96 is cammed sidewardly (toward the left as seen in FIGURE 5) against the bias force of a latching spring 100 until the bottom end of the latching lug 94 moves above the latch 96 (see FIGURE 4). The latch 96 then will move sidewardly (toward the right as seen in FIGURE 5) to bring the latching shoulder 102 of the latch 96 beneath the lug 94 thereby securely holding the clip 14 within the gun body 12. In order to release the clip 14 from the gun body 12, the latch 96 may be unlocked by depressing the latch button 104 which extends outwardly of the gun body 12 (see FIGURE 1) and moving the latch 96 against the bias force spring 100. The latching shoulder 102 will then move out of engagement with the latching lug 94 and the clip 14 will fall from the cavity 34 by the force of gravity. A child playing with the gun 10 may thereby easily remove one clip 14 from the gun 10 and replace it with another clip.

As detailed above, each of the individual clips 14 has a cover 46 which may be rotated about the pivot 48 thereby providing easy access for the reloading of the clip with a new roll R of caps. A child may engage in realistic play with the gun 10 in simulation of an actual automatic pistol by replacing an empty cap clip 14 with a fully loaded clip.

An important feature of the construction in accordance with the present invention is the provision of a body 12 for a cap pistol which is free from a requirement for large sized openings at either the top or the sides of the gun. As will be appreciated, the only opening necessary in the cap gun 10 is the opening to the clip receiving cavity 34 at the lower end and a smaller opening at the other end for the discharge of the expended cap strip S. This construction allows for a stronger gun body to be formed of conventional material such as cast or stamped metal and cast or molded plastics and thus allows ease of design and providing attachments to a gun in simulation of the attachments which may be secured to an actual automatic pistol.

It will be appreciated that there is provided in accordance with the present invention a cap gun construction of improved design and improved fidelity to prototype automatic pistols. Although only one illustrative embodiment of the invention has been described herein and illustrated in the drawings, a large number of design variations are possible without departing from the teachings of the present invention. The most obvious changes would be the incorporation of an identical or similar clip in cap guns of other types such as rifles, machine guns, etc. Furthermore, a cap-firing mechanism and in particular the cap clip in accordance with the present invention, may be incorporated into an infinite variety of toys. Accordingly, the following claims should be construed broadly in accordance with the spirit and scope of the invention.

What is claimed is:

1. A cap-firing toy gun comprising a gun body having a handle portion, a barrel portion and a trigger mounted on said gun body and movable between an inactive position and a firing position, said handle portion being formed with a clip-receiving internal cavity, said toy gun further comprising a clip having a clip body, a cap firing mechanism including an actuating lever, hammer means and anvil means mounted within said clip body, said clip being slidably received within said clip-receiving cavity with said actuating lever position to be engaged by said trigger to actuate said cap-firing mechanism when said trigger is moved into its firing position, and releasable securing means including latch means and latching lug means on said clip body and said gun body engageable when said clip is slidably received in said clip-receiving cavity.

2. A cap-firing toy gun comprising a body having a handle portion, a barrel portion and a trigger mounted

on said body and movable between an inactive position and a firing position, said handle portion being formed with a clip-receiving internal cavity, said toy gun further comprising a cap storing and firing clip including a clip body, a cap firing mechanism mounted within said clip body including an actuating lever, hammer means, and anvil means and cap storage means, said clip being slidably received within said clip-receiving cavity with said actuating lever positioned to be engaged by said trigger to actuate said cap-firing mechanism when said trigger is moved into its firing position, and releasable means including a spring loaded latch mounted on one of said clip body and said gun body and a latching lug formed on the other of said clip body and said gun body engageable when said clip is slidably received in said clip-receiving cavity for releasably securing said clip within said clip-receiving cavity.

3. A cap gun comprising a gun body, guide means on said gun body defining a clip-receiving cavity, a trigger mounted on said gun body and having a firing extension movable between an inactive position removed from within said clip-receiving cavity and a firing position extending into said cavity, a clip sized to be received within said cavity and having means cooperating with said guide means for guiding said clip for sliding movement into and out of said clip-receiving cavity, said clip having cap storage means and cap advancing and firing means including anvil means, hammer means and an actuating lever secured to said clip, said actuating lever located on said clip at a position for cooperative engagement with said firing extension of said trigger for advancing and firing caps in said clip upon movement of said trigger from said inactive to said firing position, and releasable securement means on said gun body and said clip respectively for releasably securing said clip within said cavity including a latch on one of said gun body and said clip and a latching lug on the other of said gun body and clip, said clip being completely removable from said gun body and separable from said trigger.

4. A cap gun comprising a gun body, guide means on said gun body defining a clip-receiving cavity, a trigger mounted on said gun body and having a firing extension movable between an inactive position removed from within said clip-receiving cavity and a firing position extending into said cavity, a clip sized to be received within said cavity and engaging said guide means during sliding movement into and out of said clip-receiving cavity, said clip having cap storage means and cap advancing and firing means including anvil means, hammer means and hammer actuating means secured to said clip, said hammer actuating means located on said clip at a position for cooperative engagement with said firing extension of said trigger for advancing and firing caps in said clip upon movement of said trigger from said inactive to said firing position, and releasable securement means on said gun body and said clip respectively for releasably securing said clip within said cavity, said clip being completely removable from said gun body and separable from said trigger.

5. A cap gun in accordance with claim 4 wherein said clip further includes a clip body having an integrally formed front wall and side wall, said side wall having means defining a cap storage area on one side thereof and a cap advancement and firing area on the other side thereof, said clip further including means on said side wall in said cap storage area for supporting a roll of caps, means on said side clip body in said cap advancement and firing area providing a pivotal mount for said hammer actuating means, said hammer means comprising a hammer lever pivotally mounted on said pivotal mount for movement from a cocked position to a firing position, spring means biasing said hammer lever into said firing position, a cocking tooth on said hammer actuating means and a hammer tooth on said hammer lever positioned in operative relationship for cocking said hammer lever against the force

of said bias means in response to initial movement of said hammer actuating means, means for causing disengagement of said teeth in response to further movement of said hammer actuating means for releasing said hammer lever for movement toward said anvil means, an actuating opening formed in said front wall at the location of said firing extension of said trigger when said clip is in said clip-receiving opening, said actuating opening providing access to said actuating means through said front wall of said clip body, said clip being loadable with a roll of caps when removed from said gun.

6. A cap gun in accordance with claim 4 wherein said clip further includes a clip body having an integrally formed front wall, rear wall and side wall, said side wall being formed with means defining a cap storage area on one side thereof and a cap advancement and firing area on the other side thereof, means on said side wall in said cap advancement and firing area providing a pivotal mount for said hammer actuating means, an actuating opening formed in said front wall at the location of said firing extension of said trigger when said clip is in said clip-receiving opening, said actuating opening providing access to said hammer actuating means through said front wall of said clip body, and a cover mounted on said clip body movable between a closed position and an open position, said clip being loadable with a roll of caps when removed from said gun and when said cover is in its open position.

7. A cap gun in accordance with claim 4 wherein said clip further includes a clip body having an integrally formed front wall, rear wall and side wall, said side wall being formed with an upstanding dividing wall defining a cap storage area on one side thereof and a cap advancement and firing area on the other side thereof, said clip further including means on said side wall in said cap storage area for supporting a roll of caps, means on said side wall in said cap advancement and firing area providing a pivotal mount for said hammer actuating means, said hammer means comprising a hammer lever pivotally mounted on said pivotal mount for movement from a cocked position to a firing position, said anvil means comprising said rear wall of said clip engageable by said hammer lever when in the firing position, spring means biasing said hammer lever into said firing position, said cap advancement means including a cap advancement link pivotally mounted on said hammer actuating means and engageable with a strip of caps extending from said cap storage area to said anvil means for advancing said strip of caps toward said anvil means in response to movement of said actuating lever, an actuating opening formed in said front wall at the location of said firing extension of said trigger when said clip is in said clip-receiving opening, said actuating opening providing access to said hammer actuating means through said front wall of said clip body, and a cover pivotally mounted on said clip body at said pivotal mount, movable between a closed position and an open position, said clip being loadable with a roll of caps when removed from said gun and when said cover is in its open position.

8. A cap gun in accordance with claim 4 wherein said clip further includes a clip body having a side wall, said side wall being formed with means defining a cap storage area on one side thereof and a cap advancement and firing area on the other side thereof, said clip body further including means in said cap storage area for supporting a roll of caps, said hammer actuating means comprising an actuating lever, means on said side wall in said cap advancement and firing area providing a pivotal mount for said actuating lever, said hammer means comprising a hammer lever pivotally mounted on said pivotal mount for movement from a cocked position to a firing position, said anvil means engageable by said hammer lever when in the firing position, spring means biasing said hammer lever into said firing position, a cocking tooth on said actuating lever and a hammer tooth on said hammer lever

positioned in operative relationship for cocking said hammer lever against the force of said bias means in response to initial movement of said actuating lever, means for causing disengagement of said teeth in response to further movement of said actuating lever for releasing said hammer lever for movement toward said anvil means, said cap advancement means including a cap advancement link pivotally mounted on said actuating lever and engageable with a strip of caps extending from said cap storage area to said anvil means for advancing said strip of caps towards said anvil means in response to movement of said actuating lever.

9. A cap gun in accordance with claim 4 wherein said clip further includes a clip body having an integrally formed front wall, rear wall and side wall, said hammer activating means comprising an activating lever, a pivot post extending upwardly from said side wall providing a pivotal mount for said actuating lever, said hammer means comprising a hammer lever pivotally mounted on said pivot post for movement from a cocked position to a firing position, said anvil means comprising said rear wall of said clip engageable by said hammer lever when in the firing position, spring means biasing said hammer lever into said firing position, a cocking tooth on said actuating lever and a hammer tooth on said hammer lever positioned in operative relationship for cocking said hammer lever against the force of said bias means in response to initial movement of said actuating lever, means for causing disengagement of said teeth in response to further movement of said actuating lever for releasing said hammer lever for movement toward said anvil means, said cap advancement means including a cap advancement link pivotally mounted on said actuating lever and engageable with a strip of caps extending from said cap storage area to said anvil means for advancing said strip of caps toward said anvil means in response to movement of said actuating lever, an actuating opening formed in said front wall at the location of said firing extension of said trigger when said clip is in said clip-receiving opening, said actuating opening providing access to said actuating lever through said front wall of said clip body, and a cover mounted on said clip body movable between a closed position substantially coextensive with said side wall and an open position, said clip being loadable with a roll of caps when removed from said gun and when said cover is in its open position.

10. A cap gun in accordance with claim 4 wherein said clip further includes a clip body having an integrally

formed front wall, rear wall and side wall, said side wall being formed with an upstanding dividing wall defining a cap storage area on one side thereof and a cap advancement and firing area on the other side thereof, said hammer actuating means comprising an actuating lever, said clip further including a post extending upwardly from said side wall in said cap storage area for supporting a roll of caps, a pivot post extending upwardly from said side wall in said cap advancement and firing area providing a pivotal mount for said actuating lever, said hammer means comprising a hammer lever pivotally mounted on said pivot post for movement from a cocked position to a firing position, said anvil means comprising said rear wall of said clip engageable by said hammer lever when in the firing position, spring means biasing said hammer lever into said firing position, a cocking tooth on said actuating lever and a hammer tooth on said hammer lever positioned in operative relationship for cocking said hammer lever against the force of said bias means in response to initial movement of said actuating lever means for causing disengagement of said teeth in response to further movement of said actuating lever for releasing said hammer lever for movement toward said anvil means, said cap advancement means including a cap advancement link pivotally mounted on said actuating lever and engageable with a strip of caps extending from said cap storage area to said anvil means for advancing said strip of caps toward said anvil means in response to movement of said actuating lever, an actuating opening formed in said front wall at the location of said firing extension of said trigger when said clip is in said clip-receiving opening, said actuating opening providing access to said actuating lever through said front wall of said clip body, and a cover pivotally mounted on said clip body at said pivot post, movable between a closed position substantially perpendicular thereto, said clip being loadable with a roll of caps when removed from said gun and when said cover is in its open position.
